UNITED STATES PATENT OFFICE.

JAMES BOLTON, OF GLEN SPEY, NEW YORK.

STAND AND COVER FOR SEWING-MACHINES.

SPECIFICATION forming part of Letters Patent No. 374,578, dated December 13, 1887.

Application filed July 24, 1886. Serial No. 208,938. (No model.)

To all whom it may concern:

Be it known that I, JAMES BOLTON, a citizen of the United States, residing at Glen Spey, in the county of Sullivan and State of New York, have invented certain new and useful Improvements in Stands and Covers for Sewing-Machines, of which the following is a specification, reference being had therein to the accompanying drawings.

The object of my invention is to provide a cheap and convenient stand and cover for sewing-machines, the cover being of such construction that the ends thereof may be turned down to form the top of the table, so that only a small table proper will be required, the sides and top of the cover being formed by a flexible sheet consisting of strips of wood flexibly connected together, and thus adapted to be run down into guideways formed in the rear legs of the side frames of the stand when the machine is uncovered. One of the side frames of the stand is provided with curved inwardly-projecting arms or braces, which are adapted to serve as a dress-guard for the driving-wheel, the latter being hung within the outer side of the same, so as to be protected thereby. I also provide a simple construction for attaching the drawers to the table.

In order that my invention may be fully understood by those skilled in the art to which it relates, I will now describe the same in connection with the accompanying drawings, in which—

Figure 1 is an elevation of a sewing-machine stand and cover embodying my invention. Fig. 2 is an enlarged detail view of the driving-wheel bearings. Fig. 3 is an end view of the stand and cover with the brackets for the side drawers omitted. Fig. 4 is a top view of one of the side frames of the stand. Figs. 5, 6, 7, and 8 are detail views of parts of the cover and table, Fig. 6 being a section on line 6 6, Fig. 5.

A and A' denote the side frames of the stand, said side frames being provided at their tops with ears a, to which the table B is attached. I preferably provide these ears on both sides of the tops of the side frames, as shown in Fig. 4, so that the table B may be so strongly attached to the said side frames that the usual cross-brace between the latter

may be omitted. The side frame A is provided with inwardly-projecting arms a', in the center of which is the hub or bearing a² for 55 the driving-wheel C. Any desired number of the arms a' may be provided, the said arms, which are preferably curved, as shown in Fig. 1, forming a guard to protect the dress of the operator from the driving-wheel, which 60 is held within the said arms, but is arranged on the outer side thereof. In the present instance only two of these arms, crossing each other, are shown; but this number may be increased, if desired. 65

The driving-wheel C is provided with a journal-pin, c, preferably cast integral therewith, as clearly shown in Fig. 2, said pin having a shoulder, c', preferably rounded, as shown, and fitting in a corresponding recess 70 in the hub a². A collar or boss, c², preferably having a rounded inner end, is attached to the pin c by a set-screw, c³, said collar thus serving to retain the driving-wheel in place. It is obvious that the collar c² may be adjusted 75 on the pin c to take up any wear in the bearings of the driving-wheel. The crank-pin c⁴ is on the outside of the said driving-wheel, and is connected by a pitman, D, with a treadle, E, pivoted in the usual manner on the 80 cross-rod F, connecting the side frames A and A', the treadle having an arm, e, which extends through the side frame A, for the attachment of the pitman.

The casing or cover, within which the head 85 of the sewing-machine, or sewing-machine proper is housed, consists of a base-piece, G, to which are hinged two end pieces, H, the lower ends of which are mitered or otherwise cut away to fit against the mitered or cut- 90 away ends of the base-piece G when the said end pieces are turned down to the position indicated by dotted lines in Fig. 1, to uncover the machine and to form extensions for the table. 95

I is a flexible sliding cover guided in grooves h' in the end pieces, H, when the latter are upright, the position of the groove for the reception of the said sliding cover in one of the said end pieces being denoted by dotted lines 100 in Fig. 3. The cover I is made, in a well-known manner, of strips of wood mounted on a sheet of canvas, leather, or other suitable flexible material.

When the sewing-machine is to be uncovered, the cover I is slid over backward through openings in the base-piece G and the table B, and is guided in grooves a^3 in the rear legs, 5 a^4 , of the side frames. The lower ends of the end pieces, H, project downward slightly below the upper surface of the table B, so that when the said pieces are upright their lower ends will abut against shoulders b, formed at 10 the outer sides of recesses b' in the said table, the said recesses being preferably concave, as more clearly shown in Fig. 8, so that the said ends will swing closely therein when the end pieces are raised or lowered. To lock the end 15 pieces, H, in vertical positions, as well as to cover the said recesses b' and the openings formed by the mitered or cut-away ends of the said end pieces and the base-piece G, I provide spring holding-plates J, the outer parts, 20 j, of which are adapted to spring under the outer edges of the mitered lower ends of the end pieces, H, or beneath the outer ends of metallic bearing-plates h, recessed into the said end pieces, so that the said spring holding-plates, when the parts are in the position 25 shown in Figs. 1 and 5, will spring beneath the said end pieces, or the bearing-plates attached thereto, and thus hold the end pieces upright. The metallic bearing-plates are preferred, as they will not be marred by contact 30 with the spring holding-plates, as the wooden end pieces might be. The sliding cover I will be provided at its front with an ordinary lock, and to prevent surreptitious access to the sewing-machine locked within said cover (which 35 might be effected by turning down the end pieces without raising the sliding cover I) the spring holding-plates J are provided with projections j', extending under the front edge 40 of the cover when the latter is over the machine, such position of the said cover relative to one of said projections being indicated by dotted lines in Fig. 7. When the cover is thus 45 down in front, the finger-notches j', which must be accessible in order to press the spring holding-plates outward, cannot be reached, so that the holding-plates cannot be released until the cover is raised.

When the machine is to be uncovered for 50 use, the operator unlocks the cover I in front and raises and slides the same over backward, so that it may run down into guideways formed by the grooves a^3 in the legs a^4 . The spring holding-plates J are then sprung outward 55 slightly to release the end pieces, H, and the latter are turned to the positions denoted by dotted lines in Fig. 1 to form the extended table-top.

It will be understood that the grooves or 60 recesses b in the upper surface of the table B may be rectangular in cross-section, instead of being concave, as shown, and also that the cut-away or recessed ends of the base-piece G and of the end pieces, H, instead of being mitered, as shown, may be otherwise constructed to fit into each other when the said end pieces are turned down horizontally.

I prefer to attach the side drawers, K, to the table by means of brackets L, provided with inwardly-projecting longitudinal ribs m, 70 adapted to fit in longitudinal grooves in the sides of the drawers to sustain the latter. These ribs are near the tops of the drawers, so that brackets like those shown at the left side of Fig. 1 are adapted to support either one or 75 two of the drawers, the brackets projecting but little below the drawer if but one is placed therein, while the brackets like those shown at the right side of Fig. 1 may be used to support either two or three drawers. As these 80 brackets may be readily attached to the machines by the agents, and as the drawers are all alike, machines with different numbers of drawers can be readily supplied, as may be desired by the purchaser, without requiring 85 the agents to carry a large stock of different styles of machines, the drawers and brackets being furnished in quantity to the agents. This construction of the supports for the side drawers is, moreover, much cheaper than the 90 ordinary wood-work framing in which drawers are mounted. The brackets L may, if necessary, be connected by cross-pieces n, of wood or metal, to steady them in place.

I am aware of the patent to Horrocks, No. 95 281,765, and do not wish to be understood as claiming the construction therein shown.

I claim as my invention and desire to secure by Letters Patent—

1. The combination, with the side frames of 100 a sewing-machine stand, the rear legs of which are provided with guiding-grooves, of a table attached to said side frames, and a cover secured to said table and consisting of a base-piece, end pieces hinged to said base-piece, 105 and a flexible sliding cover adapted to run down into the guiding grooves in the rear legs of the side frames.

2. The combination, with the table provided with grooves or recesses in its upper 110 surface, having shoulders at their outer sides, and the base-piece of the cover having cut-away or recessed ends, of the hinged end pieces, the lower ends of which are adapted to swing in the said grooves or recesses and to 115 abut, when the said end pieces are vertical, against the said shoulders at the outer sides of said grooves or recesses.

3. The combination, with the table having 120 grooves or recesses in its upper side and the base-piece of the cover having cut-away or recessed ends, of the hinged end pieces cut away or recessed at their lower ends, and the spring holding-plates adapted to cover the front sides of the recesses in the table, the base-pieces, 125 and the end pieces, and to retain the last-named pieces in vertical position.

4. The combination, with the table B, the base-piece G, and the spring holding-plates J, of the hinged end pieces, H, provided with 130 the metallic bearing-plates h, beneath which said plates J spring to retain said end pieces in vertical position, substantially as set forth.

5. The combination, with the table B, the

base-piece G, the hinged end pieces, H, and the sliding flexible cover I, of the spring holding-plates J, having projections j' extending beneath the front of the said sliding cover 5 when the latter is in position over the sewing machine.

6. The side frame A, having the integral inwardly-projecting arms a' , adapted to serve as a dress-guard, and the central hub or bearing, a^2 , combined with the driving-wheel C, journaled in said hub or bearing and arranged on the outer side of said arms and within the outer side of the side frame.

7. The combination, with the driving-wheel C, having the integral journal-pin c^1 , of the 15 boss or collar c^2 , attached to said wheel, and the bearing a^2 , having recesses for the reception of said shoulder and collar.

In testimony whereof I affix my signature in presence of two witnesses.

JAMES BOLTON.
